UNITED STATES PATENT OFFICE.

ALFRED COTTON, OF ST. LOUIS, MISSOURI, ASSIGNOR TO HEINE BOILER COMPANY, OF ST. LOUIS, MISSOURI, A CORPORATION OF MISSOURI.

METHOD AND APPARATUS FOR PRODUCING SECTIONAL BOILER HEADERS.

Application filed August 4, 1923. Serial No. 655,670.

To all whom it may concern:

Be it known that I, ALFRED COTTON, a citizen of the United States, residing at St. Louis, Missouri, have invented a certain 5 new and useful Improvement in Methods and Apparatus for Producing Sectional Boiler Headers, of which the following is a full, clear, and exact description, such as will enable others skilled in the art to which 10 it appertains to make and use the same.

This invention relates to methods and apparatus used in the manufacture of sectional boiler headers of the kind that are produced by deforming a wrought iron or 15 drawn steel tube in such a way as to convert it into a hollow member, capable of use as a header for a vertical row of boiler tubes, and of such form that a plurality of such 20 members can be arranged side by side, in nested relation.

One object of my present invention is to provide a novel method for producing a hollow member of substantially rectangular cross section from a round or oval tube.

25 Another object is to provide a novel apparatus for carrying out said method.

I have herein illustrated my method and apparatus as being used to produce a sectional boiler header, but I wish it to be 30 understood that the method and apparatus can be used in the manufacture of various other hollow members.

Briefly described, my method consists in arranging a heated metal tube in a die 35 whose cavity is of the same shape or approximately the same shape of the member or article which it is desired to produce, and thereafter expanding said tube into engagement with the die by internal 40 pressure that is exerted outwardly on portions of the tube progressively, in such a way that the tube will be changed gradually from its original cross section into a hollow member whose exterior conforms to 45 the shape of the die. Various means may be used for expanding the tube into engagement with the die, but I prefer to gradually fill the tube with a non-compressible 50 substance or medium which is of such a nature or character that it can be easily discharged from the tube at the completion of the deforming operation, and subjecting said substance or medium to such action as to cause it to exert outward pressure on the

tube and force the tube outwardly into engagement with the die. One medium that is well adapted for this purpose is sand, or a similar granular material, but it is obvious that various other substances or mediums could be used without departing 55 from the spirit of my invention. Owing to the fact that the tube is deformed progressively by expanding one portion of the tube, then an adjacent portion and so on throughout the length of the tube, less power is required to deform the tube than if all portions of the tube were deformed at the same time. It is immaterial what type or kind 60 of means is used for exerting pressure on the medium that forces the tube outwardly 65 into engagement with the die, but one means that is highly satisfactory consists of a plunger arranged to move longitudinally of the tube and act on said medium, said plunger being operated in such a way that 70 it will cause said medium to be subjected to sharp, sudden blows in rapid succession, or operated in such a way that it will exert 75 gradually increasing pressure on said medium each time a forward stroke is imparted 80 to said plunger.

Various forms of apparatus can be used for practicing my method. The apparatus herein illustrated consists of a die in which a heated tube is adapted to be arranged, 85 means for introducing a granular substance into said tube so as to gradually fill the same, and means for exerting pressure on said substance in such a way as to cause the tube to be expanded progressively into engagement with the die by the outward force 90 or pressure said substance exerts on the tube. The means that exerts pressure on the granular substance in the tube consists of a pulsating plunger that moves longitudinally of the die in which the tube is arranged, and means is provided whereby at the beginning of the deforming operation said plunger will be arranged at one end 95 of the die, and as the deforming operation proceeds, one of said elements, either the plunger or the die, will travel longitudinally relatively to the other element, so as to bring different zones of the die into operative relationship with the plunger. In 100 the machine herein illustrated the pulsating plunger is carried by a stationary part of the apparatus and the die is carried by a 105

movable part of the apparatus arranged so as to cause the closed end of the die to travel away from the operating end of the plunger as the tube in the die is gradually filling up with the granular substance, but it is, of course, obvious that the same effect could be obtained by mounting the die on a stationary part of the apparatus and moving the plunger bodily relatively to the die, so as to bring the plunger into operative relationship with different zones of the die.

Figure 1 of the drawings is a vertical sectional view of an apparatus constructed in accordance with my invention, for practicing my improved process.

Figure 2 is a side elevational view of the die and the platform on which it is mounted.

Figure 3 is a top plan view of the die; and

Figure 4 is a vertical longitudinal section of a portion of the die, illustrating how adjacent portions of the tube are expanded progressively into engagement with the die.

I have herein illustrated my method and apparatus used to produce a sectional boiler header of approximately oblong shape in horizontal cross section, as indicated by the reference character x in Figure 3, and provided with at least two opposed sides that are corrugated or of sinuous form in general outline, as shown in Figures 1 and 4. The tube from which the header is constructed will usually consist of a wrought iron or drawn steel tube that is of circular shape or oval shape in cross section, as shown in broken lines in Figure 3, as my invention overcomes the necessity of partially deforming a round tube in one machine and then placing the tube in another machine in which the final shape or form is imparted to the tube.

Referring to the drawings, the reference character A in Figure 1 designates as an entirety a die whose cavity corresponds to the external shape of the header to be produced in the apparatus. Said die is arranged in an upright position on a vertically-movable platform B with the upper end of said die open, so that a tube y can be arranged in the die and sand or some other suitable substance z thereafter fed into the tube, so as to gradually fill the same. After the tube has been partly filled with the substance z said substance is subjected to pressure by means of a reciprocating plunger C that extends downwardly into the tube, so as to cause the substance z to exert outward pressure on the tube and cause a portion of the tube to be forced outwardly into engagement with the zone of the die in proximity to the portion of the tube filled by the substance z . More of the substance z is then introduced into the tube and the platform B is moved simultaneously in a direction to bring the plunger C into operative relationship with

a different zone of the die, the pressure which said plunger exerts on the substance z in this new position of the plunger and die causing another portion of the tube to be forced outwardly into engagement with the die. The above described operations are continued, namely, sand or the like is fed gradually into the tube and the die is moved relatively to the plunger, thereby causing the tube to be deformed progressively and in such a way that by the time the platform B has reached its limit of travel in one direction all portions of the tube will have been expanded into the die, said die being of such construction that one or more parts of same can be moved or detached at the completion of the deforming operation, so as to permit the header to be removed from the die.

In the machine herein shown the plunger C is carried by a stationary part of the apparatus and is arranged above the die A in longitudinal alignment with the cavity of the die, the platform B being provided with a depending guide or piston 1 that projects through a stationary, horizontally-disposed guide 2, and thus maintains the die A in parallel relationship with the plunger C during the deforming operation. Various means can be used to raise and lower the platform B, but I prefer to use an hydraulic means to move said platform upwardly so as to arrange the zone at the lower end of the die A in operative relationship with the plunger at the beginning of the deforming operation, and use gravity to move said platform downwardly, so as to bring the successive zones of the die into operative relationship with the plunger, the downward movement of the platform B being governed by the escape of sand 3 from a chamber or cylinder 4 into which the depending guide 1 on the platform B projects. As shown in Figure 1, a plurality of hydraulic cylinders 5 are arranged under the platform B parallel to the sand chamber 4, and the pistons 5^a of said hydraulic cylinders are disposed vertically and connected at their upper ends to said platform, the operating medium that is supplied to and exhausted from the cylinders 5 being controlled by a three-way valve 6. Sand or the like is introduced into the upper end of the sand chamber or cylinder 4 by a feed pipe 7 that leads from a supply hopper 8, and said sand chamber is provided at its lower end with a discharge outlet 9 through which the sand escapes from said chamber gradually during the deforming operation, thereby permitting the platform B to descend gradually and move the die A downwardly from its starting position or extreme elevated position indicated by dotted lines in Figure 1 when sand is being fed into the upper end of the tube, it being understood that when the valve 10 that con-

trols the discharge outlet 9 of the sand chamber 4 is open, as shown in Figure 1, the three-way valve 6 of the hydraulic mechanism is set so as to permit the operating medium to escape from the cylinders 5.

The substance *z* that co-operates with the plunger C to expand the tube into the die is fed into the upper end of the tube by a feed pipe 11 that leads from the sand supply hopper 8 and which is equipped with a valve 12 that can be adjusted so as to govern the admission of the sand to the tube and cut off the flow of sand through said feed pipe. The feed pipe 7 through which sand 10 is admitted to the sand chamber or cylinder 4 is also equipped with a regulating valve, designated by the reference character 13 in Figure 1, and a means such as an elevator 14 15 is used for conveying the sand that escapes 20 from the sand chamber 4 upwardly into the supply hopper 8.

I have herein illustrated the plunger C as being moved downwardly by the piston of a steam cylinder 15 and moved upwardly by a 25 spring 16 arranged between a head piece 17 on said plunger and a stationary guide 18 in which the plunger reciprocates, but I wish it to be understood that it is immaterial what 30 type or kind of means is used for operating said plunger, and it is also immaterial whether said plunger is pulsated or operated at a high speed, or operated in such a way that it exerts gradually increasing pressure 35 on the substance *z* in the tube during its downward or forward stroke.

The die A is preferably provided with rollers 19, as shown in Figure 2, so as to facilitate the movement of same onto and off of the platform B, and in order that said 40 die will have a square, even bearing on the platform during the operation of deforming the tube, the spindles or axles of the rollers 19 are carried by eccentrics 20 mounted in lugs on the die A in such a way that when 45 handles 21 that are combined with said eccentrics are moved in one direction, the die will be moved upwardly off of the platform B and supported by the rollers 19, and when said handles are moved back to normal position, the die will be lowered onto the platform. In Figure 3 of the drawings I have 50 illustrated one form of die that is particularly adapted for use in the manufacture of a boiler header produced by deforming a tube, on account of its great strength and 55 rigidity and the ease with which it can be assembled and disassembled. As shown in said figure, the die is composed of two members 23 arranged in opposed relation and provided on their inner sides with inwardly-projecting portions 23^a that form two of the 60 sides of the die, two opposed members 24 arranged in opposed relation at right angles to the members 23, bolts 25 that pass transversely through the members 24 and through

the inwardly-projecting portions 23^a of the members 23, and bolts 26 that connect the members 23 to angularly-disposed flanges 24^a on the members 24.

After the tube has been arranged in the die A, said die is set in an upright position on the platform B and said platform thereafter moved upwardly by manipulating the valve 6 of the hydraulic raising mechanism for the platform, thus causing the plunger 70 C to be brought into operative relationship with the zone at the lower end of the die. The valve in the sand supply pipe 11 is then opened so as to cause sand to be fed into the tube in the die, the plunger C is set in operation, the valve 6 is positioned so as to permit the hydraulic medium to escape from the cylinders 5 and the discharge valve 10 of the sand cylinder 4 is opened so as to permit 75 the sand in the cylinder 4 to escape therefrom. The pressure which the plunger C exerts on the sand that fills the lower end portion of the tube causes this portion of the tube to be expanded or forced outwardly 80 into engagement with the die, and as the platform B moves downwardly, due to gravity and to the gradual escape of sand from the sand cylinder 4, different zones of the die will be brought into operative relationship 85 with the plunger, thus causing other portions of the tube to be expanded progressively 90 into engagement with the die.

Having thus described my invention, what I claim as new and desire to secure by Letters Patent is:

1. A method of making a hollow member, characterized by arranging a heated tube in a die, expanding the portion adjacent one end of the tube into engagement with the die, and thereafter expanding other portions of the tube into engagement with the die in regular progression from one end of the tube to the other.

2. A method of making a hollow member, characterized by arranging a heated tube in a die, introducing a non-compressible medium into a portion of the tube, subjecting said medium to such action as to cause that portion of the tube to be expanded into engagement with the die, and repeating the above operations on other portions of the tube so as to progressively deform the tube.

3. A method of making a hollow member, characterized by arranging a heated tube in a die, feeding sand or the like into the tube, and exerting pressure on said sand in a direction lengthwise of the tube as the sand fills up the tube, so as to cause the sand to force different portions of the tube into engagement with the die progressively.

4. A method of making a hollow member, characterized by arranging a heated tube in a die, filling one end portion of the tube with a non-compressible medium, subjecting said medium to pressure by a reciprocating

plunger arranged inside of the tube so as to expand the filled portion of the tube into engagement with the die, and continuing the supply of the non-compressible medium to the tube and simultaneously changing the relative position of the plunger and tube by moving one of said elements longitudinally with relation to the other, whereby the tube will be deformed progressively.

10 5. A method of making a hollow member, characterized by arranging a heated tube in a die, positioning a plunger inside of said tube adjacent the closed end of the die, feeding sand or the like into the tube so as to gradually fill the same, reciprocating said plunger so as to cause it to exert pressure on the sand in a direction to expand the tube, and changing the relative position of the plunger and die so as to bring the plunger into operative relationship with different zones of the die and thus cause the tube to be deformed progressively.

20 6. A method of making a hollow member, characterized by arranging a heated tube in a die, positioning a plunger inside of said tube adjacent the closed end of the die, feeding sand or the like into the tube so as to gradually fill the same, reciprocating said plunger so as to cause it to exert pressure on the sand in a direction to expand the tube, and moving the die in a direction longitudinally of the plunger so as to cause the tube to be forced outwardly progressively into engagement with the die as the tube becomes filled 30 with said sand.

40 7. A method of making a hollow member, characterized by arranging a heated tube in a vertically-disposed die that is mounted on a platform, positioning a plunger inside of said tube adjacent the lower end of the die, moving the platform downwardly gradually and simultaneously feeding sand or the like into the tube, and reciprocating the plunger so as to cause it to exert pressure on the sand in a direction to progressively expand the tube into engagement with the die.

50 8. An apparatus for producing a hollow member from a tube, comprising a die in which a tube is adapted to be arranged, a reciprocating plunger arranged to move longitudinally of said tube, means for feeding sand or the like into the tube so as to cause the plunger to exert pressure on said sand in a direction to expand the tube into engagement with the die, and means for changing the relative position of the plunger and tube while the sand is being fed into the tube so as to bring the plunger into operative relationship with different zones of the die and thus cause the tube to be deformed progressively.

60 9. An apparatus for producing a hollow member from a tube, comprising a die in which a tube is adapted to be arranged, a reciprocating plunger carried by a station-

ary portion of the apparatus and arranged to move longitudinally inside of the tube in said die, means for feeding sand or the like into said tube into a position to be acted upon by said plunger, so as to expand the tube, and means for moving the die longitudinally relatively to the plunger as the tube is filling up with sand so as to cause the tube to be deformed progressively.

10 10. An apparatus for producing a hollow member from a tube, comprising a platform, a die arranged in an upright position on said platform and adapted to have a tube positioned inside of same, a reciprocating plunger arranged to move longitudinally inside of said tube, means for raising and lowering said platform for the purpose described, and means for gradually filling the tube with a non-compressible medium when the platform is moving downwardly away 80 from the plunger.

11. An apparatus for producing a hollow member from a tube, comprising a platform, a die arranged in an upright position on said platform and adapted to have a tube positioned inside of same, a reciprocating plunger arranged to move longitudinally inside of said tube, means for raising said platform to locate the plunger in proximity to the zone at the lower end of the die, means for feeding sand or the like into the upper end of the tube in the die, and means for causing the platform to move downwardly at such a speed when sand is being supplied to said tube that the tube will be deformed 90 progressively by the joint operation of said plunger and sand.

12. An apparatus for producing a hollow member from a tube, comprising a platform, a die arranged in an upright position on said platform and adapted to have a tube positioned inside of same, a reciprocating plunger arranged to move longitudinally inside of said tube, means for raising said platform to locate the plunger in proximity to the zone at the lower end of the die, means for feeding sand or the like into the upper end of the tube in the die, a depending guide on said platform that projects into a sand cylinder, and means for permitting the sand to escape from said sand cylinder gradually when sand is being fed into the upper end of the tube so as to permit the platform to move downwardly and thus cause the tube to be deformed progressively.

13. An apparatus for producing a hollow member from a tube, comprising a platform, a die arranged in an upright position on said platform and adapted to have a tube positioned inside of same, a reciprocating plunger arranged to move longitudinally inside of said tube, means for raising said platform to locate the plunger in proximity to the zone at the lower end of the die, means for feeding sand or the like into the upper end 125

of the tube in the die, a depending guide on said platform that projects into a sand cylinder, means for permitting the sand to escape from said sand cylinder gradually when sand is being fed into the upper end of the tube so as to permit the platform to move downwardly and thus cause the tube to be de-

formed progressively, an elevated sand supply hopper from which sand is taken to fill the tube and to fill the sand cylinder, and means for conveying the sand that escapes from the sand cylinder upwardly to said supply hopper.

ALFRED COTTON.
